UNITED STATES PATENT OFFICE.

JOHN M. BROCK, OF BROOKLYN, NEW YORK.

ACETYLENE-LAMP.

1,269,047.

Specification of Letters Patent. Patented June 11, 1918.

Application filed October 2, 1915. Serial No. 53,725.

To all whom it may concern:

Be it known that I, JOHN M. BROCK, a citizen of the United States, residing at Brooklyn, county of Kings, and State of New York, have invented certain new and useful Improvements in Acetylene-Lamps, fully described and represented in the following specification and the accompanying drawings, forming a part of the same.

10 This invention relates to improvements in acetylene lamps and particularly miners' acetylene cap lamps.

The object of the invention, broadly considered, is to provide a simple means where- 15 by the flame will be supplied with air, while at the same time it will be protected against strong drafts such as would be likely to blow it out, and also will be protected against water dripping from a mine roof or the like.

20 With the above general object in view and some others which will be obvious to those skilled in the art, the invention consists in the features, details of construction and combinations of parts which will first be described in connection with the accompanying drawings and then particularly pointed out 25 in the claims.

In the drawings—

Figure 1 is an elevation partly in section 30 of a well known type of lamp, with the invention applied thereto;

Figs. 2, 3 and 4 are enlarged detail views illustrating the invention;

Fig. 5 is a detail view of one modification 35 of the invention;

Fig. 6 is a similar view of another modi- 40 fication;

Fig. 7 is a front view of a cap or thimble.

Referring to Fig. 6, which shows the 45 simplest form of the invention, A indicates a part of a lamp from which extends a burner-tube B, provided with a burner C, this being indicated as an ordinary lava burner tip, which is inserted tightly in the burner tube.

Over the burner tube is placed a cap or thimble D arranged to form a chamber about the burner-outlet or orifice. The front wall of this chamber is provided with an opening d in line with the burner-orifice and of such a size that the flame may extend through said opening so as to appear in front of the chamber or cap.

The cap is also provided with an opening or openings for the admission of air to the gas as it emerges from the burner ori-

fice. In the present example these air inlets are arranged in the front wall of the cap around the flame-opening, as indicated at d', Figs. 6 and 7.

The cap is arranged to be held in place detachably so that it may be removed to permit access to the burner, so that the latter may be cleaned or removed and replaced by another burner.

In the simple embodiment of the invention shown in Fig. 6 of the drawings, the exterior of the burner-tube B, at the front end, is threaded and the cap D is correspondingly threaded interiorly so that it may be screwed 70 into the burner-tube.

The air holes d' are advantageously made of such size that they will tend to throttle the flow of air through them, so that when a heavy draft of air strikes the cap, the air 75 will flow gently through the holes and therefore cannot blow out the flame. Furthermore, when, as in the best embodiment of the invention these air holes are arranged around the flame opening in the front wall of the 80 cap, the air passing through the holes will not strike the burner orifice, but will strike the end of the burner around the burner-orifice. This serves to check the speed of the air and allows it to reach the flame in a 85 quiet condition. The number of air holes may be such as to supply all the air that is required to support combustion and thus maintain the flame. By this construction, the body of air in the chamber is kept hot 90 and the incoming cold air is thereby heated up by commingling with the air in the chamber before reaching the gas.

Where a reflector is provided, as is generally the practice with miners' lamps, the 95 cap serves the further function of detachably holding the reflector in place against the reflector support. This is shown, for example, in Fig. 6, where E is the reflector and F is the reflector-support behind it. The 100 reflector has an opening which will permit it to pass over the burner tube, but which is smaller than the outer diameter of that part of the cap B which contacts with the reflector.

105 It is obvious that by removing the cap from the burner tube, the reflector may be taken off and replaced.

While the construction shown in Fig. 6 is very satisfactory, I have found that by employing a special form of burner, as herein-after explained, still better results are ob-

tained. This preferred embodiment of burner is illustrated in Figs. 1 to 4.

This burner is provided with a sleeve portion G screw-threaded to the end of the burner-tube B and has an enlarged head whose diameter is greater than that of the sleeve. This enlarged head has a burner orifice g which is preferably coned at the front. From this coned portion extend radial slots, 10 as indicated at g' , Fig. 3. The outer wall of these radial slots merge into a peripheral groove g^2 in the edge of the enlarged head, as shown in Fig. 2.

The cap or thimble D' is provided with 15 one or more inward extending projections d^2 , Figs. 2 and 4. These may be made conveniently by pressing or indenting the circular wall of the cap, as indicated in Fig. 4. When a plurality of such inward-extending 20 projections are employed, as is advantageous, the said projections should be so spaced apart that when the cap is put onto the end of the burner tube they will register with and enter the corresponding slots in the 25 burner. This will enable them to be brought in line with the peripheral groove g^2 , whereupon, by rotating the cap, the indentations will enter the groove g^2 and hold the cap D' in place.

With a burner of this special type, the 30 diameter of the cap may be conveniently made greater than in the construction shown in Fig. 6, without the necessity of employing a special burner tube, and the depth of the 35 chamber thereby reduced while still having a sufficient interior volume.

At the same time, the air holes d' though 40 closer to the burner in an axial direction, may be kept farther away radially so that this incoming air cannot injuriously affect the flame. The cap of shallower depth axially has the advantage that more of the 45 flame will project beyond the cap.

Owing to the radial slots g' in the burner, 45 the heating surface for heating the air in the chamber is materially increased.

With a special burner of this type, the reflector may be held in place detachably either by the end of the sleeve G, as shown 50 in Fig. 5, or the reflector may be held by the cap itself as shown in Fig. 1, according to the length of the burner tube and the size of the reflector support. The construction shown in Fig. 1 is advantageous 55 because the flame is protected better by a shallow reflector.

Owing to the fact that the burner orifice is protected against strong drafts of air, it is difficult, if not impossible, for the flame 60 to be blown out accidentally.

This is particularly advantageous where a reflector is employed, because such reflectors, when employed with open burners, serve to direct drafts of air against the flame 65 and thus increase the dangers of accidental

extinguishment. When the cap is used in advance of the reflector it prevents the concentration of drafts of air on the flame by the reflector and even when the flame is struck by a heavy draft directly from the 70 front and is blown back, the gas will generally continue to burn at the mouth of the burner orifice and hence, as soon as the draft is stopped the flame will again lengthen and project beyond the cap. 75

Obviously water dripping into the reflector or onto the cap cannot reach the burner and therefore cannot extinguish the flame.

What I claim is:

1. In an acetylene lamp, the combination, 80 with a burner tube, and a burner connected therewith and having a burner-orifice, of a cap surrounding the burner and arranged to form a flame-surrounding chamber into which the burner-orifice opens, said cap having a flame opening ahead of the burner-orifice through which opening the flame passes and also having an opening for admitting air to the interior of the chamber at a point away from the burner orifice, the 90 flame opening being so large as compared to the burner orifice, and the relation of said opening and orifice to the opening for admitting air being such, that under normal operating conditions the base of the flame is 95 within said chamber.

2. In an acetylene lamp, the combination, 100 with a burner-tube, and a burner connected therewith and having a burner-orifice, of a reflector, a reflector support, and a cap surrounding the burner and arranged to form a flame-surrounding chamber into which the burner-orifice opens, and also arranged to hold the reflector against its support, said cap having a flame opening ahead of the 105 burner orifice through which opening the flame passes and also having an opening for admitting air to the interior of the chamber at a point away from the burner-orifice, the flame opening being so large as compared to the 110 burner orifice, and the relation of said opening and orifice to the opening for admitting air being such, that under normal operating conditions the base of the flame is within said chamber. 115

3. In an acetylene lamp, the combination, 120 with a burner-tube, and a burner connected therewith and having a burner-orifice, of a cap connected to the burner and forming a flame-surrounding chamber into which the burner-orifice opens, said cap having a flame-opening in its front wall substantially in line with the burner-orifice through which opening the flame passes and also having a plurality of air-inlet openings substantially 125 smaller than the flame opening arranged to supply air to the chamber out of the direct path of the flame.

4. In an acetylene lamp, the combination, 130 with a burner-tube, and a burner connected

therewith, said burner having a burner-orifice and grooves in its face connected with said orifice, of a cap connected to the burner and forming a chamber into which the 5 burner-orifice opens, said cap having a flame-opening in its front wall substantially in line with the burner-orifice and also having a plurality of air inlet openings arranged to supply air to the chamber out of the direct 10 path of the flame.

5. In an acetylene lamp, the combination, with a burner tube, and a burner connected therewith, said burner having an enlarged 15 circular front portion provided with a peripheral groove and having a burner-orifice and grooves extending from said orifice and merging into the peripheral groove, of a cap having a plurality of inward projections arranged to enter corresponding grooves in the 20 burner and to lock with the peripheral groove, said cap also having a flame-opening in its front wall substantially in line with the burner-orifice and also having a plurality 25 of air-inlet openings arranged to supply air to the chamber out of the direct path of the flame.

6. In an acetylene lamp, the combination, with a burner-tube, and a burner connected therewith, said burner having an enlarged 30 circular front portion provided with a peripheral groove and having a burner-orifice and grooves extending from said orifice and merging into the peripheral groove, of a

Copies of this patent may be obtained for five cents each, by addressing the "Commissioner of Patents, Washington, D. C."

cap having a plurality of inward projections arranged to enter corresponding grooves in the 35 burner and to lock with the peripheral groove, said cap also having a flame-opening in its front wall substantially in line with the burner-orifice and also having a plurality of air-inlet openings arranged to supply air to the chamber out of the direct 40 path of the flame, a reflector support and a reflector arranged to be pressed against the support by the cap.

7. In an open-flame portable acetylene 45 lamp, the combination, with a reflector, a burner-tube, and a burner connected therewith and having a burner orifice, of a cap arranged in front of the reflector surrounding the burner and arranged to form a flame- 50 surrounding chamber, said cap having an opening large enough to permit the passage of the flame through it, said opening being ahead of the burner orifice, the cap also having its front wall provided with an opening 55 for admitting air to the interior of the chamber at a point away from the burner orifice.

In testimony whereof, I have hereunto set my hand in the presence of two subscribing 60 witnesses.

JOHN M. BROCK.
